UNITED STATES PATENT OFFICE.

JOHN DESMOND, OF CHICAGO, ILLINOIS, ASSIGNOR TO ARTIZAN BRASS COMPANY, OF CHICAGO, ILLINOIS, A CORPORATION.

COMPOUND PUMP.

No. 909,163.

Specification of Letters Patent.

Patented Jan. 12, 1909.

Application filed April 9, 1906, Serial No. 310,623. Renewed November 6, 1908. Serial No. 461,382.

To all whom it may concern:

Be it known that I, JOHN DESMOND, a citizen of the United States, and a resident of Chicago, county of Cook, and State of Illinois, have invented certain new and useful improvements in Compound Pumps, of which the following is declared to be a full, clear, and exact description.

The improvement relates to small portable compound pumps for automobile tires and the like; and seeks to provide a simple construction which may be inexpensively manufactured and which may be readily taken apart for repairs and the like.

15 The invention consists in the features of construction, combinations and arrangements of parts hereinafter set forth, illustrated in the accompanying drawing and more particularly pointed out in the appended claims.

20 In the drawings Figure 1 is a view in longitudinal section of the improved pump. Figs. 2 and 3 are sections on lines 2—2 and 3—3 respectively of Fig. 1.

25 The pump comprises a large low pressure cylinder 10 and a small high pressure cylinder 11 arranged side by side and provided with one-way yielding, oppositely-acting, cup-leathers or pistons 12 and 13. The cylinders communicate at their upper ends and the lower end of the large cylinder is provided with an inlet, while the lower end of the small cylinder is provided with an outlet. The piston rods 14 and 15 are connected to and are simultaneously operated by a common handle 16. In pumps of this sort the ends of the cylinders are usually threaded into a cap and foot pieces. Such mode of construction is defective, the parts cannot 30 be easily assembled nor can they be readily taken apart for repairs and the like. It is highly desirable that the parts of such a pump can be readily disconnected since the flexible cup-leathers or pistons often become 35 hard and dry so that they will not work properly.

40 In the present improved construction, the cylinders 10 and 11 are formed of pieces of plain metal tubing (preferably of brass) cut to proper length and arranged in contact side by side. The ends of the cylinders are unthreaded but snugly fit within and are brazed to a base or foot piece 17 and a flange member 18. The foot piece 17 is of cast 45 metal and, as shown, is provided with a tread

portion 19 so that the pump will be securely held in upright position by the operator's foot. The base piece is provided with an upstanding flange 20 shaped to snugly fit about the lower ends of the cylinders and the lower ends of these cylinders are placed within the flange 20 and securely brazed thereto.

50 The foot piece is provided with an inlet or orifice 21 opening into the lower end of the large low pressure cylinder. The foot piece has a boss 22 at one side having a bore or discharge outlet 23 leading from the lower end of the small high pressure cylinder 11. An upstanding nipple 24 communicates with the bore 23 and is arranged to receive the end of the flexible tube 25 by which the pump may be placed in communication with the tire or the like. A portion of the bore 23 is enlarged and a seat for a ball valve 26 is formed 55 between the enlarged and contracted portions of such bore or outlet. A plug 27 is removably threaded within the outer end of the bore and is provided at its outer end with a head or flange 28 that abuts against the end 60 of the boss 22 to prevent leaking at this point. A coiled spring 29 arranged between the plug 27 and the valve 26, holds the latter yielding against its seat and prevents any 65 back flow from the tube 25.

70 The flange member 18 is formed of cast metal and is shaped to fit snugly about the upper ends of the cylinders 10 and 11. The latter are placed within the flange member with their upper edges in line with the upper 75 face thereof and are securely brazed to the member. After the cylinders have been brazed within the flange member 18 the upper edges thereof and the upper face of the flange member are planed so that they present a smooth, flat surface. A packing strip 80 30 of suitable material and a cap plate 31 of cast metal, are provided. The packing strip and cap plate correspond in outline to the flange member 18 and are secured in place 85 over the upper ends of the cylinders, with the packing strip between the flange member 18 and cap plate 31, by screws 32 extending through ears 33 and 34, that are correspondingly formed upon the cap plate and flange 90 member. The lower face of the cap plate 31 is planed to present a true, flat surface and the headed screws 32 extend loosely through the ears 33 of the cap plate and are threaded 95 into the ears 34 of the flange member 18. 100

105

110

Two sets of the ears 33 and 34 through which the connecting screws 32 extend, are arranged at opposite ends of the cap plate 31 and flange member 18, and two sets are arranged intermediate the ends of these parts at points between the cylinders, as shown in Figs. 2 and 3. By this arrangement the cap plate 31 may be easily secured in position or removed when desired. But when in position, will effectively prevent leaking around the upper ends of the cylinders.

The piston rods 14 and 15 extend upwardly through openings in the packing strip 30 and the cap plate 31 and the latter are provided with suitable stuffing boxes 35 having glands 36 that surround the rods. The packing strip 30 between the piston rods, is cut away as at 37 (see Fig. 3) and the cap plate 31 is provided on its under face with a channel or groove 38 that places the upper ends of the cylinders in communication. This communicating port or passage in prior constructions has been formed in the walls of the cylinders, but when so arranged its edges are apt to cut and wear the cup-leathers or pistons.

The low pressure cup-leather or piston 12 is upturned while the high pressure cup-leather 13 is downturned, as shown. These cup-leathers or pistons are held in place upon the lower reduced ends of the piston rods 14 and 15 between plates or washers 39, by nuts 40 threaded thereon. The pistons are arranged opposite each other, as shown, and the upward movement thereof is arrested by engagement of the upper plate 39 of the high pressure piston with the cap-plate 31, and the down stroke of the piston is limited by the engagement of the lower plate or washer 39 of the low pressure piston with the foot piece 17. These parts are so arranged that the yielding edge of the cup-leather 12 may closely approach the cap plate 31 and the edge of the downturned cup-leather 13 may closely approach the foot piece 17, but without being jammed against these parts. The upper reduced ends of the piston rods 14 and 15 extend through the central portion of the cross bar or handle 16 and are secured thereto by nuts 41. The opposite ends of the cross bar are provided with gripping portions 42 and the rods, as shown, are connected to the handle bar at equal distance from its ends, so that the pressure will be uniformly applied to the rods and pistons without side strain thereon.

The operation will be readily understood. On the down stroke air will be drawn in through the inlet 21, past the low pressure piston 12 and into both of the cylinders. On the up stroke piston 12 will expand and snugly engage the wall of the large piston 10 and will compress the air in both cylinders past the yielding high pressure piston and

into the lower end of the small high pressure cylinder. On the next down stroke, the high pressure piston 13 will expand and snugly engage the walls of its cylinder 11 and finally compress the air beneath it out through the discharge outlet 23 and past the check valve 26 therein to the nipple 24, pipe 25 and tire to which the latter is connected. At the same time the cylinders are again filled with air.

The improved construction described may be inexpensively manufactured. The parts can be readily assembled and should the cup-leathers become hard and dry, misshapen or worn out so that the pump does not operate properly, they may be readily repaired or renewed by removing the screws 32 and cap plate 31 and the parts then quickly and readily assembled.

It is obvious that the details set forth may be varied without departure from the essentials of the invention.

Having described my invention, what I claim as new and desire to secure by Letters Patent is:—

1. A compound pump comprising large and small cylinders formed of tubing and arranged side by side, a cast metal foot piece fitting upon and brazed to the lower ends of said cylinders, a flange member fitting over and brazed to the upper ends of said cylinders, a cap plate upon said flange member, an intermediate packing strip between said plate and flange member, screws detachably connecting said flange and cap plate, one-way yielding, oppositely-acting pistons in said cylinders having piston rods extending through said cap plate and a common handle to which the upper ends of said rods are connected, said cap plate having stuffing boxes about said piston rods, and a channel on its under face communicating with said cylinders, and said foot piece having an inlet opening into the large cylinder and a valved outlet leading from the small cylinder, substantially as described.

2. A compound pump comprising large and small cylinders formed of tubing and arranged in contact side by side, a cast metal foot piece fitted upon and brazed to the lower ends of said cylinders, a flange member fitting over and brazed to the upper ends of said cylinders, a cap plate upon said flange member and an intermediate packing strip between said plate and flange member, screws detachably connecting said parts, one-way yielding, oppositely-acting pistons in said cylinders having piston rods extending through said cap plate, a common handle to which the upper ends of said rods are connected, said cylinders communicating at their upper ends and having an inlet and outlet at their lower ends respectively, substantially as described.

3. A compound pump comprising large and small cylinders formed of tubing and arranged in contact side by side, a cast metal foot piece having an upturning flange within which the lower ends of said cylinders fit and whereto they are brazed, a flange member fitting over and brazed to the upper ends of said cylinders, a cap plate corresponding in outline to and mounted upon said flange member, an intermediate correspondingly shaped packing strip between said plate and flange member, screws detachably connecting said parts and extending loosely through the perforated ears in said cap plate and threaded into corresponding ears in said flange member, one-way yielding, oppositely-acting pistons in said cylinders having piston rods extending through said cap plate and a common handle to which the upper ends of said rods are connected, said cylinders communicating at their upper ends and having an inlet and an outlet at their lower ends respectively, substantially as described.
4. A compound pump comprising large and small cylinders formed of tubing and arranged side by side, a cast metal foot piece fitting upon and brazed to the lower ends of said cylinders, a flange member fitting over and brazed to the upper ends of said cylinders, a cap plate upon said flange member, an intermediate packing strip between said parts, screws detachably connecting said flange member and cap plate, one-way yielding, oppositely-acting pistons in said cylinders having piston rods extending through a cap plate and a cross bar or handle to which said rods are connected at points equally distant from the end thereof, said cap plate having stuffing boxes about said piston rods and a channel on its under face communicating with said cylinders, and said foot piece having an inlet opening into the large cylinder and a valve outlet leading from the small cylinder, substantially as described.
5. A compound pump comprising large and small cylinders formed of tubing and arranged in contact side by side, a cast metal foot piece having an upstanding flange within which the lower ends of said cylinders fit and whereto they are brazed, a flange member fitting over and brazed to the upper ends of said cylinders, a cap plate upon said flange member, an intermediate packing strip between said plate and flange member, screws detachably connecting said flange and cap plate, one-way yielding, oppositely-acting pistons in said cylinders having piston rods extending through said cap plate and a common handle to which the upper ends of said rods are connected, said cap plate having stuffing boxes about said piston rods and a channel on its under face communicating with said cylinders and said foot piece having an inlet opening into the large cylinder and an outlet bore communicating with said small cylinder and an upstanding nipple communicating with said bore intermediate its ends, a ball check valve in said outlet bore, a plug threaded into the outer end thereof and a coiled spring between said plug and valve, substantially as described.
6. A compound pump comprising large and small cylinders formed of tubing, arranged side by side and secured together at their lower ends, a flange member fitting over and brazed to the upper ends of both of said cylinders, a cap plate extending over the ends of both of said cylinders and over said flange member, an intermediate packing strip between said plate and said flange member and screws detachably connecting said parts, one way yielding, oppositely acting pistons in said cylinders having piston rods extending through said cap plate, a common handle to which the upper ends of said rods are connected, said cap plate having stuffing boxes about said piston rods, and said cylinders communicating at their upper ends and having an inlet and outlet at their lower ends respectively, substantially as described.
7. A compound pump comprising relatively large and small cylinders formed of tubing and arranged side by side, a metal piece fitting upon and secured to the lower ends of both of said cylinders, a flange member fitting over and secured to the upper ends of both of said cylinders, a common cap plate extending over the upper ends of said cylinders and over said flange member, an intermediate packing strip between said plate and flange member, screws detachably connecting said plate and flange member, one way yielding, oppositely acting pistons in said cylinders having piston rods extending through said cap plate, and a common handle to which the upper ends of said rods are connected, said cap plate having stuffing boxes about said piston rods, the metal piece secured to the lower ends of said cylinders having an inlet opening into the large cylinder and a valved outlet leading from the small cylinder, and said cylinders communicating at their upper ends, substantially as described.
8. A compound pump comprising relatively large and small cylinders formed of tubing and arranged side by side, a cast metal piece fitted upon and brazed to the lower ends of both of said cylinders, a flange member fitted over and brazed to the upper ends of both of said cylinders, a common cap plate extending over the outer ends of said cylinders and over said flange member, an intermediate packing strip between said parts, one way yielding, oppositely acting pistons in said cylinders having piston rods extending through said cap plate, and a

common handle to which the upper ends of said rods are connected, said cylinders having a communication at their upper ends at a point between the adjacent edge portions thereof and said cap plate, and said cast metal piece having an inlet opening into the large cylinder and a valved outlet leading from the small cylinder, substantially as described.
